UNITED STATES PATENT OFFICE.

THOMAS PRENTICE, OF SOUTHBURY, CONNECTICUT.

PLIERS.

Application filed August 22, 1925. Serial No. 51,858.

My invention relates to improvements in pliers of the form having in combination with certain well-known and ordinary features, such as provision for grasping and gripping bolts, nuts, small pipe, and wire, and for cutting wire, means for facilitating the removal of cotter-pins, tacks, and the like; and the object of my improvement is to produce superior means for operating upon cotter-pins, involving the use of main jaws that are particularly adapted for gripping the head loops thereof, whether in the normal shape and condition or more or less deformed, and also a relatively enlarged fulcrum structure of rounded form for providing a relatively elongated roller bearing under working conditions, and which bearing structure is constructed in the form of auxiliary jaws that are the counterpart of the main jaws and located in offset relation of said main jaws.

In the accompanying drawing:—

Figure 1 is a side face view of my improved pliers as viewed from the side showing the head of the pivotal screw and the slot for shifting the operative bearing;

Fig. 2 is a view from the reverse face;

Fig. 3 is a side edge view;

Fig. 4 is an end elevation as viewed from the jaw end;

Fig. 5 is a sectional view on the line 5—5 of Fig. 4; and Fig. 6 is a sectional view on the line 6—6 of Fig. 3.

My improved pliers comprise the pivotally connected mating members consisting of the upper member 10 and the lower member 11 and the pivotal pin of screw 12 and nut 13. The pivotal pin 12 has the head 14 that is opposed to the upper member 10. Said upper member has the short slot 15 that terminates by its ends in the circular end bearings 16 for permitting of shifting the operating bearing for the members 10 and 11 in the usual manner.

The members 10 and 11 have handles 17 of the usual form at one side of the pivotal pin 12 and at the other side thereof certain operative jaw features of common form. Thus adjacent the pin 12 and provided in the overlapping face portions 18 are the cooperating cutting recesses or slots 19 for cutting wire.

Outward from the overlapping portions 18 the members 10 and 11 are provided with offset bends 20 so as to bring the outer jaw structures 21 into substantially the same

plane, and to bring the inner edge face of one member in direct opposition to the inner edge face of the mating member. Parts of said inner edge faces are finished, shaped, and provided with gripping teeth of ordinary form. Thus adjacent the offset bend 20 the opposed faces 22 are of concave form and are provided with relatively coarse teeth for gripping small pipe and the like, and outward from said curved faces 22 are opposed relatively flat faces 24 having finer teeth 25.

Coincident with the flat-faced jaws 24 and as viewed from the side of the lower member 11 are certain lug structures 26 that pertain to the present invention, and outward from the same are the main jaws 27 of the invention.

Said main jaws 27 are of appreciable length and the inner opposed edge faces 28 are of concave curved form and not adapted for close gripping or the like, the shape being such as to confine the active gripping action to the extreme ends or tips 29. The outer boundary wall or face 30 of each of the main jaws 27 is rounded to conform generally with the inner curved face 28 so that the main jaws 27 in side face view appear as cooperating and relatively sharp horns or gripping noses. The bounding faces 31 of the main jaws 27 are of tapered form, converging towards the tip 29, so that the active tip structure 29 is relatively sharp, being bounded on all sides by converging walls or faces.

The lug structures 26 are offset inwardly from the active jaw tips 29; project outwardly from the adjacent faces 32 of the members 10 and 11; and they may be briefly described as being the counterparts of the main jaws 27. Thus each lug structure 26 is in the form of an auxiliary jaw that has the relatively sharp tip 29^a, the curved inner wall or face 28^a, the curved outer wall or face 30^a, and the converging front and rear faces 31^a.

There are many situations as to cotter-pins that involve no special difficulty and in which there would be little choice as to which of the jaws of the invention would be used, and either the main jaws 27 or the auxiliary jaws 26 could be used. It is in special situations that the utility of the invention appears and in which the main jaws 27 engage with the work and the structures of the auxiliary jaws 26 operate as roller

bearing devices, the members 10 and 11 being actuated by the handles 17. In such use, the rounded faces 30^a serve as the active fulcrums or bearings.

5 The main or central lines of the individual jaws, extending inwardly from the tips, are of curved form, as seen at or adjacent 28 and 28^a in Figs. 5 and 6.

The mating jaws of each pair have tips 10 closely opposed or substantially in contact when in closed position and the outer walls or faces meet at the point of contact so as to form a substantially continuous curve.

The two sets of jaws are closely adjacent, 15 the one pair being substantially in alignment with the handles and the other pair being projected individually from the faces of said one pair. Also, as to details, the gripping jaws of one pair are substantially iden-

tical with the jaws of the other pair, and they provide, by the construction and arrangement described, a roller-bearing fulcrum on which they can be effectively tilted so as to get a varying purchase on the cotter-pin operated upon.

25

I claim as my invention:—

In pliers for use in extracting cotter-pins, two pairs of gripping jaws that are substantially identical, the one pair with the other, the jaws of one pair being projected individually from the faces of the jaws of the other pair, the jaws being each of curved form and cooperating one with the other so as to provide a roller-bearing fulcrum on which they can be effectively tilted so as to get a varying purchase on a cotter-pin.
